CAN COVER REMOVER

George C. Erb, Forest Hills West, N. Y., assignor
to American Can Company, New York, N. Y., a
corporation of New Jersey

Application September 5, 1945, Serial No. 614,534

4 Claims. (Cl. 220—43)

1

The present invention relates to containers or cans having opening devices for removing reclosure covers therefrom and has particular reference to a prying lever opener which is permanently and loosely attached to the covers for prying action between a cover and its container at different places around the cover for prying it from the container.

An object of the invention is the provision of a prying lever opener for a container wherein the opener is simple in construction and economical to produce and which may be permanently applied to a container reclosure in such a manner that it can be shifted around the periphery of the reclosure for prying action at different places while at the same time being disposed so that it will not interfere with stacking of the containers where such stacking is desired.

Numerous other objects and advantages of the invention will be apparent as it is better understood from the following description, which, taken in connection with the accompanying drawings, discloses a preferred embodiment thereof.

Referring to the drawing:

Figure 1 is a perspective view of a sealed container embodying the instant invention.

Fig. 2 is an enlarged vertical sectional view of the upper portion of the container shown in Fig. 1, with parts shown in elevation.

Fig. 3 is an enlarged side view of the upper portion of the container, with parts broken away and shown in section and with the opening device in one of its positions incidental to removing the container cover; and

Figs. 4 and 5 are enlarged sectional details taken substantially along the respective lines 4—4, 5—5 in Fig. 2.

As a preferred embodiment of the invention the drawings illustrate a sheet metal cylindrical can having top and bottom countersunk panel end members 12, 13, respectively, secured thereto in any suitable manner, such as for example, by well known double seams 14. The top member 12 is formed with an upright annular neck wall section or portion 16 (Fig. 2) which extends up from a countersunk panel 17 and terminates in an inwardly extending curled edge 18 the top of which is disposed in a plane preferably flush with or slightly above the top edge of the double seam 14. This curled edge 18 defines a dispensing opening 19 for the container.

The dispensing opening 19 is sealed with a reclosure cover or cap 22. This reclosure cover is formed with a countersunk dome shaped panel 23 (Figs. 2, 4 and 5) the outer peripheral edge of which merges into an upright or upstanding annular inner friction wall section 24. This annular wall section frictionally engages against the inner surface of the curled edge 18 of the container and thus holds the cover in place when the cover is on

5

2

the can. The upper end of the wall section 24 merges into a curved flange 25 which extends over the curled edge 18 of the container and this flange portion merges into a depending outer annular cover wall section 26. The outer wall section extends down adjacent the neck section 16 of the container in spaced relation thereto, as shown in Fig. 2, and terminates in a smooth annular edge curl or pry-off edge 27.

The outer wall section 26 and the inner wall section 24, connected by the curved flange 25, thus set off an inverted U-shaped channel 28 which encloses the curled edge 18 and the neck section 16 when the cover 22 is in place on the can. A sealing gasket 29 of rubber compound or other suitable material is disposed in the channel 28 and thus provides a hermetic seal between the cover flange 25 and the curled edge 18 of the can.

A pry-off opening lever 35 is provided for prying off the cover 22 when it is desired to open the can. This lever is made preferably of heavy sheet metal and is permanently and loosely attached to the outer depending wall section 26 of the cover so it can be shifted around the peripheral edge of the cover to any desired place to pry the cover loose. The opening lever includes a relatively long curved vertical side wall 36 (Figs. 1, 2 and 4) which is disposed normally adjacent to and parallel with the edge curl 27 of the cover 22. One end of the lever is formed with a handle or actuating pad 37 which extends outwardly from and at right angles to the upper edge of the curved wall 36.

The opposite end of the wall section 36 is formed with an upwardly disposed rounded cam edge 38. Intermediate the ends of the lever, closely adjacent the cam end, the curved wall section 36 is formed with a narrow locking lug 39 (Figs. 2 and 4) which extends laterally and inwardly under the edge curl or pry-off edge 27 of the cover 22 and then upwardly at right angles into the space between the outer depending wall section 26 of the cover and the upright neck wall section 16 of the can, as best shown in Fig. 4.

The upper inner end of this lug terminates closely adjacent the gasket 29 in the channel 28.

Cooperating with the locking lug 39 to hold the pry-off lever on the cover is a lateral wall or shelf section 42 which extends inwardly from the upper edge of the lever side wall section 36. This lateral wall section 42 extends substantially from the actuating pad 37 rearwardly of the lever and is adapted to contact with the top surface of the cover pry-off edge 27 to support the lever and to hold it in its normal or inoperative position, as shown in Fig. 1. Near the cam end of the lever the lateral wall section 42 curves or extends upwardly and terminates opposite the locking lug 39 in close proximity to the outer surface of the depending wall section 26 of the cover (Fig. 4).

Thus with the lateral wall section 42 of the lever disposed on one side of the depending wall section 26 of the cover and the locking lever lug 39 disposed under the pry-off curl and on the opposite side of the cover wall section 26, the lever 35 is retained in a loose but permanent connection with the pry-off edge of the cover. This permits of shifting the lever around the periphery of the cover to different places for prying the cover loose. This prying action is readily effected at any desired place around the cover, by a mere lifting of the lever by its actuating pad 37, as best shown in Fig. 3.

This lifting action brings the cam edge 38 of the lever 35 into engagement against the countersunk panel 17 of the top end member 12 and with this cam edge as a fulcrum the locking lug 39 engages against the bottom surface of the pry-off edge 27 of the cover and thus pries the cover loose with the continued lifting of the lever.

With such a construction of opening lever, the lever is disposed normally in an inoperative position in the space between the cover and the end seam of the can and is thus in an out-of-the-way place where it is always ready for use and at the same time protected against injury. In this normal position the lever in no way interferes with stacking of the cans 11 if such stacking is desired.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container comprising in combination, a neck wall portion projecting outwardly from and surrounding an opening therein and terminating in a curled seat edge, a reclosure cover for said opening, said cover having a peripheral channel engageable over said curled seat edge and defined by an inner upstanding wall frictionally engageable with said curled seat edge and an outer depending wall disposed in spaced and substantially parallel relation to said inner wall and to said neck wall portion, said outer wall terminating in a curled pry-off edge, and a cover pry-off lever permanently and loosely connected with the curled pry-off edge of said cover and movable around said cover for prying action between the pry-off edge and a part of the container at any locality, around the cover for removing the cover from the container, the connection between said lever and the cover including a lug on the lever extending into the space between said container neck wall portion and said depending cover wall.

2. A container comprising in combination, a neck wall portion projecting outwardly from and surrounding an opening therein and terminating in a curled seat edge, a reclosure cover for said opening, said cover having a peripheral channel engageable over said curled seat edge and defined by an inner upstanding wall frictionally engageable with said curled seat edge and an outer depending wall disposed in spaced and substantially parallel relation to said inner wall and to said neck wall portion, said outer wall terminating in a curled pry-off edge, and a cover pry-off lever disposed adjacent said curled pry-off edge and having a cam end, said lever also having a lateral

wall portion extending along one edge thereof for supporting the lever on the pry-off edge of said cover, said lateral wall portion terminating adjacent the outer surface of said depending outer wall of the cover, said lever adjacent its cam end having a locking lug extending beneath said cover pry-off edge and thence outwardly between the depending outer wall of said cover and said outwardly projecting container neck wall portion to a locality adjacent the lateral wall portion of the lever for permanently and loosely connecting the lever to the cover, whereby said lever is freely movable around the cover and vertically tiltable to bring its cam end into engagement with the container with a prying action at will around the cover for removing the cover from the container.

3. A container comprising in combination, a neck wall portion projecting outwardly and surrounding an opening therein and terminating in a curled seat edge, a reclosure cover for said opening, said cover having a peripheral channel engageable over said curled seat edge and defined by an inner upstanding wall frictionally engageable with said curled seat edge for holding the cover in place on the container and by an outer depending wall disposed in spaced and substantially parallel relation to said inner wall and to said container neck wall portion, the depending outer wall of said cover terminating in a curled pry-off edge, and a cover pry-off lever having inwardly extending spaced lateral extensions disposed on opposite sides of said cover pry-off edge and terminating in opposing relation on opposite sides of the depending outer wall of the cover for permanently and loosely connecting the lever with the cover, one of said lever extensions terminating in an outwardly projecting locking lug disposed in the space between said container neck wall portion and said outer depending cover wall, whereby said lever is freely movable around the cover for prying action between said cover pry-off edge and the container at any locality around the cover for removing the cover from the container.

4. The combination of a container having an upstanding wall, a countersunk cover having a channel defined by an upstanding inner wall frictionally engaging said container wall and a depending outer wall spaced outwardly from the container wall and terminating in a curl, and a cover removing lever permanently and loosely attached to said cover for pry-off engagement with said container, the attachment of said lever to the cover including a lever part engageable exteriorly of the cover curl and an opposed lever part engageable interiorly of said curl and extending into the space between said container wall and said depending cover wall.
